CARL OTTO, OF BOCHUM, GERMANY

REGENERATIVE COKE OVEN

Application filed February 17, 1925. Serial No. 9,787.

My invention relates to regenerative coke ovens and more particularly to such ovens which may be heated with either rich or lean gas and in which the heating flues are divided 5 into groups, the inner groups of flues preferably comprising respectively more than two heating flues.

One of the objects of my invention is to so group the heating flues of each heating wall 10 of a horizontally elongated oven (the oven chamber having two opposite horizontally extending heating walls) and to combine the groups of regenerators with the groups of heating flues, the regenerators extending at 15 a lower level longitudinally of the oven chambers, that preheated air or preheated air and gas may be supplied by accessible, regulatable conduits, and burned in the heating flues in such a way as to reduce the length of the path 20 of travel of the heating flames, and also make it possible to regulate the amount of heat supplied to different groups of flues along the heating wall.

To accomplish these results, the inner 25 groups of flues contain, respectively, a plurality of flues which are connected at their top ends at the bottom of each of which gas is supplied at intervals, there being a plurality of vertical flues in each group, the 30 groups of a heating wall being arranged in pairs side by side and there being more than one group in each half of the interior of the oven heating wall. The regenerators are arranged in rows to supply preheated air or 35 preheated air and gas at the bottoms of the flues so as to cause the burning gases to flow upwardly in the same direction in the flues of adjacent interior groups of one half of the wall, the burning gases and products of 40 combustion from one of the interior groups, being discharged into the other adjacent interior regenerator of the row. On reversal, the direction of flow thru the group of flues is reversed.

45 In the form of the invention illustrated, I provide a fewer number of regenerators extending longitudinally of the heating walls than there are groups of heating flues in the wall, some of the regenerators supplying at 50 least two groups of flues. Air and gas are

supplied to their respective regenerators from the accessible outside by means of conduits connecting the regenerators with the outside faces of the oven, where the gas and air supply can be easily and accessibly regulated. 55 Rich unheated gas may be introduced by accessible underburners located in passages beneath the oven.

Furthermore, in consequence of the reduction in pressure necessary to force the burning gases along the heating walls, the difference in pressure that exists between the burning gas in the heating walls and the gas in the oven chamber, is very much reduced. 60 This avoids leakage between the walls and 65 the oven chambers. The output of the oven can be greatly increased and larger amounts of heating gas flames can pass in short paths thru the flues of the heating walls without introducing a large difference in pressure between the inlet and outlet of the flames. 70 With the ordinary horizontal oven in which the heating wall is divided into two halves, such great difference in pressure occurs 75 between the flame inlet and the flame outlet 80 halves of the heating wall, that it is practically impossible to secure the same pressure in the oven chamber as in the heating walls and leakage between the oven chamber and the wall is, consequently, increased.

With the above and other objects in view, my invention consists in the parts, improvements and combinations more fully pointed out hereinafter.

Referring now to the drawings, which illustrate two embodiments of the invention:

Fig. 1 is a vertical, longitudinal section passing thru the heating wall and showing the heating flues divided into groups and the regenerators below the flues divided into related groups.

Fig. 2 is a vertical cross-section on line 2—2 of Fig. 1.

Fig. 3 is a horizontal section on line 3—3 of Fig. 1.

Fig. 4 is a vertical longitudinal section passing thru a heating wall, showing a different embodiment of the invention.

Fig. 5 is a vertical cross-section on line 5—5 of Fig. 4.

Fig. 6 is a horizontal cross-section on line 6-6 of Fig. 4.

In the form of oven shown in Fig. 1, the flues of each heating wall are divided into six groups of vertical flues, although a greater or less number of groups may be utilized. Group 7, comprises flues 7a, 7b; group 8, heating flues 8a, 8b, 8c; group 9 heating flues flues 9a, 9b, 9c; group 10, heating flues 10a, 10b, 10c; group 11, heating flues 11a, 11b, 11c and group 12 comprises heating flues 12a, 12b.

When, for example, the flue groups 8, 9 and 12, burn upwardly, then groups 7, 10 and 11, burn downwardly and vice versa. In accordance with the invention and to supply the heating gases to the groups so as to preserve the flow as described, a smaller number of regenerator groups are provided than there are flue groups. In the best embodiment of the invention, a regenerator is supplied for each two groups of flues in the interior of the oven, there being one regenerator for each exterior group of flues at the ends of the oven. As illustrated in Fig. 1, only four groups of regenerators extending lengthwise of the oven chambers, are used, see groups 3, 1, 3a, 1a, when making use of the above number of six groups of heating flues. When the regenerators 1, 1a, see Fig. 1, are being fed upwardly thru pipes 100, 101, and connected passageways, one of which may be provided with inclined gas deflecting bottom 303, then regenerators 3, 3a, are being supplied downwardly with off-heat, discharged at 102, 103. Each flue directly communicates with its regenerator by a transverse passage 30.

In the form of the invention illustrated in Figs. 1 to 3, two rows of gas regenerators, running lengthwise of the oven chamber are utilized for each pair of heating walls of an oven chamber. Preheated air is supplied by two rows of air regenerators, one for each heating wall. When the regenerators 1, 1a, of adjacent rows, are used for preheating gas, see Fig. 1, the regenerators 2, 2a, are used for preheating the air. The regenerators 3, 3a, and 4, 4a, are then supplied with waste heat. Upon reversal, the regenerators 3, 3a of the gas rows, are supplied with gas, and 4, 4a, of the air rows, with air, whereas the regenerators 1, 1a, and 2, 2a, are then supplied with waste heat. Partition walls 1b, running crosswise of the oven chambers, divide the regenerators into groups so that the burning gases may be discharged from one group into the adjacent group and regenerator and dividing walls 1c, may be used to separate the flues of one group from the adjacent group.

In the above description and construction, I have described the oven as heated with lean gas and air, but the oven may be heated, if desired, with rich gas. In such a case, the

gas regenerators instead of being supplied with gas, are, each of them, supplied with air. Rich gas is separately supplied to each flue by means of a supply system made up of burner pipes 13, 14, which are in turn supplied from the rich gas mains 15, 16, located in passages beneath the regenerators. As illustrated, each gas main supplies one half of the heating flues, so that alternately each half of the flue groups may be supplied with gas. This avoids leakage of the gas from the regenerators.

In the preceding form of the invention, each heating wall has its system of regenerators. These systems are disconnected from each other. When shutting down one heating wall for repairs, one need merely to shut off the regenerators and burners supplying that wall. This will not affect the other heating walls.

A simpler form which, while preserving the advantage of maintaining a low difference in pressure in the heating flues, making it possible to preserve a pressure substantially equal to that of the heating flues in the oven chambers, thus avoiding leakage and permitting regulation of the heat along the heating wall, is shown in Figures 4, 5 and 6. In this form of the invention only one row of regenerators arranged lengthwise of each row of oven chambers, is employed, for two side heating walls. Each side heating wall is provided with six groups of heating flues as before, numbered 15, 16, 17, 18, 19 and 20, and, at a lower level than the oven chamber, corresponding to these heating flues, there is arranged a row of regenerators 21, 22, 23, 24. This oven may be operated with preheated lean gas and preheated air. The alternate rows of regenerators 21, 22, 23 and 24, work with lean gas. The lean gas is supplied, for example, to regenerators 22 and 24, from beneath, as thru passageways 25, 26, the gas rising thru these regenerators and being preheated and then burning in groups of heating flues 20, 16 and 17, and descending thru flue groups 19, 18 and 15, into regenerators 21, 23. Each regenerator is connected to a pair of heating walls adjacent to the cooking chamber 27, by means of connecting passageways 28, 29, see Figure 5. Preheated air is supplied for combustion with the preheated gas by means of adjacent rows of groups of regenerators constructed similarly to those for preheating the gas. These preheating air regenerators are numbered 30, 31, 32 and 33, see Figure 6. When the gas is supplied as above described, preheated air rises in regenerators 31, 33 and unites with the gas supplied thru burners 34, coming from the regenerators 22 and 24, the flame then rising thru the respective groups of heating flues and the burning gas then descending thru the flues of the other groups, the products of combustion passing into the air regenerators

33, 30, as well as into the gas regenerators 21, 23. Each of the air regenerators 33, 32, 31 and 30, is connected by two sets of connecting passages 35, to the heating flues and burners of the two heating walls adjacent to 5 the coking chamber.

The oven may be reversed at intervals, in which case the regenerators 21, 23, supply the gas and regenerators 32 and 30 supply the air, to products of combustion discharging 10 into the remaining regenerators.

Rich gas can be supplied to the oven by the underburner system, the gas going into pipes 36, 37, located in accessible passages 15 beneath the oven, and rising in the burner pipes 38, 39. If it is desired that the oven shown in Figures 4 to 6, is to be heated only by rich gas, the regenerators may be supplied with air instead of with weak gas and the rich gas supplied thru the gas pipes and 20 burner pipes. In this case the regenerators of a row lying in the direction of the oven chamber need be connected with only one heating wall.

Means are provided for heating the flues of 25 the heating walls adjacent to the ends of the oven, with greater heat than toward the middle of the oven, the end faces of the oven having a tendency toward cooling because of 30 their radiation of heat toward the outside. By these means, moreover, a large difference 35 in pressure in the flow of the gases along the heating wall and consequent leakage to the oven chamber, is avoided. The end gas passages 34, in Figure 4, and the gas passages 300 in Figure 1, as well as the air passages supplied by the corresponding end regenerators in these figures, are made of larger 40 cross-section so as to supply more gas and air than the passages in the interior of the oven. More gas and more air and greater heat are consequently supplied at the ends of the wall, at the same time preserving a slight difference in pressure in the flow of the gas. 45 It is not then necessary to dam back the flow of burning gases at the top of the flues by means of the regulating valves 301 of Figure 6, and 302 of Figure 1.

Having thus described the invention and 50 its construction and operation, it will be understood that changes may be made in carrying the invention into effect, without departing from the principle thereof. For example, the oven chambers may be vertical 55 chambers with horizontal flues for the heating walls and the regenerators may be arranged vertically.

What I claim is:

A regenerative coke oven battery comprising 60 a series of alternate horizontally elongated coking chambers and heating walls therefor arranged side by side in a row, each of said heating walls comprising vertical combustion flues arranged in exterior groups 65 and interior groups, each exterior group con-

sisting of two flues, and the flues of each exterior group being less in number than the flues of the neighboring interior group, means for communicably connecting the flues of each exterior group to the flues of the neighboring 70 interior group at their upper end, and exterior and interior regenerators arranged in ows below and lengthwise of the oven chambers and communicably connected to the flues of said exterior and interior groups, respec- 75 tively.

In witness whereof, I have signed my name to this specification.

CARL OTTO.
